DESIGN FOR A ROLL PAPER DISPENSER

Eli Lestage, New Bedford, Mass.

Application November 4, 1947, Serial No. 142,294

Term of patent 14 years

(Cl. D4—3)

To all whom it may concern:

Be it known that I, Eli Lestage, a citizen of the United States of America and a resident of the city of New Bedford, in the county of Bristol, Commonwealth of Massachusetts, have invented a new, original, and ornamental Design for a Roll Paper Dispenser, of which the following is a specification, reference being had to the accompanying drawing, forming part thereof.

Fig. 1 is a front elevation of a roll paper dispenser, showing my new design, with a roll of paper shown therein in broken lines.

Fig. 2 is a plan view thereof.

Fig. 3 is a side elevation thereof.

I claim:

The ornamental design for a roll paper dispenser, substantially as shown and described.

ELI LESTAGE.
